[57] CLAIM

The ornamental design for a hair band, as shown and described.

DESCRIPTION

FIG. 1 is a top plan view of a hair band showing my new design;

FIG. 2 is a right side elevational view thereof;

FIG. 3 is a front elevational view thereof;

FIG. 4 is a bottom plan view thereof;

FIG. 5 is a left side elevational view thereof; and,

FIG. 6 is a rear elevational view thereof.

The position of some of the folds and stitched edges varies in the disclosure due to the flexible nature of the design.
